UNITED STATES PATENT OFFICE.

FREDERICK K. NORTH, OF BOSTON, MASSACHUSETTS.

MULTISPINDLE MACHINE.

1,207,611.

Specification of Letters Patent.

Patented Dec. 5, 1916.

Application filed June 3, 1916. Serial No. 101,612.

To all whom it may concern:

Be it known that I, FREDERICK K. NORTH, a citizen of the United States, and resident of Boston, county of Suffolk, State of Massachusetts, have invented an Improvement 5 in Multispindle Machines, of which the following description, in connection with the accompanying drawing, is a specification like characters on the drawing representing 10 like parts.

This invention relates to improvements in metal working machines of the multi-spindle type in which a series of spindles for carrying the work or suitable tools are mounted 15 in a rotatable turret and a series of coöperating holders for the tool or for the work are similarly arranged about the same axis, with means for rotating the turret step by step so that each piece of work is successively operated upon by each tool and all of 20 the tools caused to operate upon the work simultaneously. Preferably the work is carried by the rotatable spindles as greater accuracy is obtained where the work is rotated than where the tool is rotated relatively 25 to the work since the rotating work always tends to return to the proper center. I have therefore illustrated my invention herein as applied to a turret carrying a series 30 of rotatable work carrying spindles.

The principal objects of the invention are to provide a machine of the above type which is capable of increased production and of greater accuracy of operation than 35 has heretofore been effected and in which the wear of the moving parts is reduced to a minimum.

So far as I am aware the automatic multi-spindle machines of the type above referred 40 to have comprised four rotating spindles and I know of no machine illustrated or described in any printed publication which comprises more than five spindles.

The machine embodying the present invention is so constructed as readily to permit the use of a greater number of spindles, six being illustrated in the accompanying drawings, thus enabling the machine to produce work requiring a greater number of operations or if duplicate tools are used to increase the amount of production.

Another feature of the invention consists in providing a reversing mechanism, preferably automatically operated within the

turret, with automatic means carried by certain of the tools for reversing the direction of rotation of the spindle so that in tapping or dieing the proper length of thread is insured.

A further feature of the invention comprises certain improvements in the mechanism for intermittently rotating the turret with means for disengaging the tool actuating mechanism of such a character that the timing of the various parts of the machine 55 will not be disturbed.

Another object of the invention is to provide an oil containing turret in which the rotating spindles and the gearing therefor are submerged, during a part of each rotation of the turret, in a body of oil, thereby 60 maintaining the same in a constant state of lubrication and reducing the wear to a minimum.

Another feature of the invention comprises means for operating the rotating work holding chucks by automatic fluid actuated mechanism, thereby providing for a quick and efficient positioning and releasing of 65 the work.

Another feature of the invention consists in improving the simplicity of the design of a multi-spindle machine by eliminating light breakable parts commonly found in machines of this character and in providing a 70 construction in which the parts are all of such rigid construction as not to be susceptible to breakage during the ordinary operation of the machine.

In general it may be stated that the main 75 object of the invention is to provide a simple compact machine of great strength and of improved accuracy in operation.

Other improvements more or less in detail will more fully appear from the following 80 specification and the accompanying drawings and will be pointed out in the annexed claims.

In the drawings; Figure 1 is a sectional view on lines 1—1 Fig. 3, the illustration 85 being made of sectional views taken in somewhat different planes in order to show the relative positions of the rotating chucks and the tool holders when in coöperating positions. Fig. 2 is a sectional view on line 2—2 90 Fig. 1 looking toward the left, Fig. 3 is a vertical sectional view on line 3—3 Fig. 1, the turret being in a slightly different posi- 95

- tion than illustrated in Fig. 1, Fig. 4 is an elevation of the right hand end of the machine shown in Fig. 1, illustrating the indexing mechanism for the turret, Fig. 5 is a similar elevation of the left hand or driving end of the machine showing the "Geneva" stop mechanism for rotating the turret, illustration of the turret being omitted, Fig. 6 is a transverse view of the turret supporting journal and hub showing the means for supplying fluid under pressure to the chuck actuating means, Fig. 7 is a detail longitudinal sectional view of the same, Fig. 8 is a detail sectional view on lines 8-8 Fig. 3 showing a portion of the hubs of the turret with the braces connecting the same and the means for actuating the clutch and the reversing cams, and, Fig. 9 is a vertical elevation of the cams illustrated in Fig. 8.
- 20 The preferred embodiment of the invention illustrated in the drawing comprises a bed 1 supporting a suitable frame 2, the ends 3 and 4 of which are provided with journals for a cam shaft hereinafter to be described. The superstructure of the lathe which is carried by the frame 2, comprises a tool holding support consisting of two preferably substantially cylindrical brackets 5 and 6 which are provided centrally 25 with relatively long bosses 7, 8 forming a journal for the main shaft 9. At the opposite end the superstructure comprises a bracket 10 having a longitudinal boss 11 forming a third journal for the main shaft 9.
- 30 A bracket 12 secured to the end piece 4 of the frame 2 and having at its upper end a journal 13 provides a convenient means for supporting a short shaft for the driving pulley 14, said shaft having a gear 15 adapted to mesh with a gear 16 upon the main shaft 9 which serves to actuate directly or 35 indirectly all of the movable parts of the machine.
- 40 The work supporting turret preferably comprises two circular heads 17, 18 having hubs 19 and 20 which are rotatably mounted respectively upon the bosses 11 and 8 of the brackets of the superstructure, said bearings being concentric with the main shaft 9.
- 45 The heads 17 and 18 are connected by strong brackets 21 preferably of the form illustrated in detail in Fig. 8. A sheet metal casing 21^x is preferably secured to said heads so that the turret when assembled is 50 in effect a closed cylinder adapted to contain a body of oil.
- 55 The heads 17 and 18 are provided with a circular series of journals adapted to receive rotatable work holding chucks. These 60 work holding chucks preferably are in the form of sleeves 22 having conoidal recesses 23 at one end to receive the chuck and at the opposite end provided with a cup shaped cylinder 24 to receive and fit the piston 25 65 which is secured to the chuck stem 26, means

being provided for introducing fluid into the chamber of the cup to act upon the piston in the manner hereinafter to be described. The chuck stem 26 is screw threaded at its opposite end and provided with collars 27, 28 adapted to retain between them the reduced end of separable chuck jaws 30 having conoidal outer surfaces adapted to coöperate with the conoidal surface 23 of the sleeve. A spring 31 seated in the recess 75 in the sleeve and bearing against the collar 27 serves normally to thrust the chuck outwardly and release the work engaged thereby. The action of the fluid pressure upon the piston 25 serves to move the chuck inwardly and clamp the same upon the work. Preferably a ball bearing 32 is interposed between the head of the sleeve and the frame in order to prevent undue friction due to the 80 thrust of the tool against the work in the 85 operation of the machine.

90 One of the improved features of the invention consists in providing means enclosed within the turret for rotating the work holding spindles and also in providing reversing means within said turret whereby the spindles may be rotated in either direction as may be desired. This is accomplished in the preferred form of the invention illustrated herein by providing each 95 spindle with two gears driven from the main shaft in opposite directions which have clutch faces adapted alternatively to engage coöperating faces upon a clutch member 100 slidably but non-rotatably secured to each 105 spindle.

110 As illustrated herein, gears 33, 34 are rotatably mounted upon the sleeve 22 adjacent the heads 17 and 18, suitable washers being placed between the gears and heads. The 105 gear 33 is actuated through a gear 35 secured to the main shaft 9 and the gear 34 is actuated through a gear 36 which is secured to the shaft 9 and engages an intermediate pinion 37 preferably mounted upon 115 a shaft 38 secured in the head 18 and which projects beyond said gears for purposes hereinafter to be described. It will be obvious that the gears 33 and 34 will be rotated in the opposite direction.

120 Any suitable clutch mechanism secured to the sleeve 22 and slidably longitudinally thereof may be utilized to cause the rotation of the spindle through either of the gears 33 or 34.

125 In the mechanism illustrated herein a central portion 22^x intermediate of the journals for the gears 33 and 34 is made hexagonal in form and a clutch 39 having an annular groove 40 is provided to embrace this hexagonal portion. The ends of the sleeve 39 preferably are provided with clutch faces to engage corresponding faces upon the adjacent ends of the gears 33 and 34. These clutch faces may if desired, be 130

formed for frictional engagement but preferably are provided with interlocking members to cause positive clutching action.

The clutch 39 is shifted longitudinally by 5 a yoke 41 embracing the clutch within the annular groove 40 and adapted to be thrust in one direction by a rod 42 extending through and beyond the heads 17 and having suitable nuts engaging the yoke as illustrated. By thrusting the rod 42 in one direction the clutch 39 may be caused to engage the gear 33 and by thrusting the rod in the other direction the clutch 29 will be released from the gear 33 and caused to engage 10 the gear 34 thus causing a rotation of the spindle in the opposite direction from that in which it is rotated by the gear 33. By this construction not only are the gears inclosed within the protecting casing of the 15 turret but also the clutch mechanism is retained therein and all of these moving parts are adapted to pass through the body of oil upon each rotation of the turret.

In the operation of machines of this character where screw cutting is performed it is 20 desirable that means shall be provided for disengaging the clutch instantly when the screw has reached the predetermined length and immediately to cause the reversal of the 25 direction of rotation of the spindle to withdraw the tool from the work.

One of the improved features of this invention comprises a means for speeding up the action of the clutch under such circumstances and in which the clutch will be actuated to reverse the direction of rotation of the spindle by the action of the tool itself. This is accomplished by providing the yoke 41 with an extension 43 apertured to pass 30 over the extension of the shaft 38. Springs 44 and 45 are provided to bear upon opposite sides of the extension 43 so that the yoke 41 will normally be held in a neutral position out of engagement with either of the gears 33 or 34. Any suitable means may be provided for supporting the outer ends of the 35 springs 44, 45, a convenient means illustrated in the accompanying drawing comprises a spider having a hub 46 and radial extensions 47 bifurcated at their ends to receive the ends of the shaft 38 and to provide a suitable support for the ends of the 40 springs 44-45. In the operation of the machine the clutch controlling rods 42 are actuated by a suitable cam to cause the engagement of the clutch with the proper gear 33 or 34 and the clutch is retained in engagement constantly by said cam. When the reversal is desired as for example, in tapping 45 or screw cutting the rod is released from the cam and preferably is shipped in the opposite direction by means carried by the tool which cooperates with the rotatable spindle at that point. This actuation by the tool not only causes the release of the clutch but the

expansion of the spring 44 serves to throw the clutch quickly into engagement with the gear which is rotating in the reverse direction, thereby causing an instant reversal of the direction of rotation of the chuck.

Any suitable mechanism may be utilized for actuating the chuck, preferably however the chuck jaws are opened and closed by fluid pressure mechanism as an "air chuck." So far as I am aware no "air chuck" has ever been applied to a machine having rotatable work holding spindles mounted in a rotating turret and I claim broadly the aforesaid combination.

As before stated the chuck stem 26 is 80 adapted to be moved longitudinally within the spindle sleeve 22 to close the chuck by air pressure within the cup 24, acting against the piston 25 which is secured to said chuck stem.

Fluid under pressure, preferably air, is introduced into the chamber aforesaid through an axial opening in the chuck stem 26, a pipe 48 leading therefrom to a hub 19 of the turret and being secured to said hub by suitable screw threaded blocks 49. The boss 11 which extends inwardly from the bracket 10 is provided with an annular air inlet groove 50 extending throughout a portion of the surface but is interrupted to form an outlet 95 pocket 51 as will more fully hereinafter appear. The air is introduced into the groove 50 by any suitable compressor through a pipe 52 communicating through a duct 53 in the frame and boss with the annular inlet aperture 50. The pocket 51 communicates with a similar duct 54 leading to the atmosphere thus providing an exhaust means for releasing the pressure upon the chuck.

In the operation of the machine the chuck jaws will be closed immediately when fluid pressure is supplied through the aperture 50 and the pipes 48 to the chuck actuating piston and said jaws will remain closed so long as this air pressure is continued. When, however, in the rotation of the turret the ends of the pipes 48 are brought opposite to the exhaust 51 the pressure upon the chuck stem piston will be released and the spring 51 will serve to force the chuck outwardly 105 and to release the work. It therefore follows that the workman is given ample time to remove the completed work and to chuck a new piece while the rotation of the turret is arrested during one operation of the tools.

Any suitable mechanism may be provided for presenting the tools to the work which is held in the rotating spindle. A preferred mechanism however is illustrated in the accompanying drawings which is so coordinated with the turret and its rotating chucks as to be always in proper timed relation therewith.

As illustrated in the drawing the tool 125 laders 55 are in the form of cylindrical 130

bars which are slidably mounted in suitable journals in the brackets or heads 5, 6, said tool holders being spaced apart sixty degrees to correspond to the position of the 5 rotatable chuck carrying spindles. The spindles are moved longitudinally in their bearings by means of a cam drum 56 which is rotatably mounted upon the bosses 7, 8 in which the main shaft 9 is journaled. The 10 cam drum may be of integral construction with suitable cam grooves cut in the periphery thereof but preferably is in the form of a cylinder having a sleeve 57 secured to the outer surface thereof, said sleeve being 15 slotted or made up in sections so as to form cam grooves of a contour to give the proper reciprocating movement to each tool. Each tool holder 55 is provided with a sleeve 58 upon which is secured a yoke 59 having extensions or trunnions 60, 61 provided with anti-friction rollers, the extension 60 being adapted to enter a cam slot in the drum and the extension 61 slidably engaging with its roller the walls of a slot 62 in a connecting 20 plate 63 secured at its ends to the heads 6 and 7 of the tool supporting portion of the superstructure. The sleeve 58 may be adjustably secured to the tool holder and the yoke also may be adjustably clamped upon said 25 30 sleeve by suitable nuts screwed upon the end of the sleeve and abutting the ends of the yoke. By reason of this adjustability the tool may be properly positioned in respect to the work.

35 The cam drum is provided with an extended hub 64 having secured thereto a gear 65 which is driven from the cam shaft of the machine in a manner hereinafter to be described.

40 Where one or more of the tools carried by the tool holders is to be utilized for tapping or screw threading it is necessary that the chuck shall be stopped and reversed to withdraw the tool. As before stated, this reversal should be practically instantaneous and certain in operation. To this end the tool holders 55 carrying the taps or dies are provided with extensions or arms 66 adapted to coöperate with the chuck actuating 45 50 rods 42. As illustrated in Fig. 1 the arm 66 forms a prolongation of the yoke which engages a cam slot in the drum. The arm 66 is bent and is journaled in a boss or bearing in the frame so that it will be caused to reciprocate in parallelism with the tool holders 55. In order further to speed up the actuation of the clutch mechanism the end of the arm 66 is provided with a preferably cylindrical cap 67 inclosing a spring 68 intermediate of the inner end of the cap and the end 60 of the rod 66, said cap being retained upon the end of the arm 66 by a pin and slot connection.

In the operation of the machine the forward movement of the tool holder 55 will

cause the end of the cap 67 to abut against the end of the rod 42 the clutch at that time being in engagement with the gears 34. As the tool 55 progresses the spring 68 is compressed until finally the force of the spring 70 and the pressure of the arm 66 is sufficient to disengage the clutch from the gear 34. The action thereupon of the spring 44 together with that of the spring 68 is sufficient to snap the clutch positively into engagement 75 with the gear 33, whereupon the direction of rotation of the spindle is immediately reversed and the tapping or screw cutting tool withdrawn. The cam drum of course may be provided with a suitable number of cam 80 slots as may be necessary to give the proper movement to each tool.

It is of course necessary in the construction of a machine of the character herein described that a proper timing relation shall 85 always be maintained between the various mechanisms. This is accomplished in the present invention by providing means for rotating the turret and means for rotating the drum and for actuating such cross tools 90 as may be provided from a single shaft which shaft also serves to actuate indexing mechanism for locking the turret in each of its stationary positions during the intermittent rotation thereof.

In the preferred embodiment of the invention illustrated in the drawing a countershaft or cam shaft 70 is mounted in the end portions 2, 3 of the frame and also supported upon an intermediate web 71 having a suitable boss 72 providing a journal for said cam shaft. The shaft 70 is driven directly from the main shaft by a beveled gear 73 which meshes with a complementary gear 74 having a hollow hub 75 rotatably mounted upon a shaft 76. The end of the hub 75 is preferably in the form of a clutch member 78 adapted detachably to engage a corresponding clutch member 79 slidably keyed to an enlarged portion 80 of the shaft 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 of the slots is cut away in arcuate form to fit the periphery of a disk 87 which is mounted upon the shaft 70. The disk 87 is provided with a radial arm 88 having a laterally extending pin 89 adapted to enter the slot 86 and thereby cause intermittent rotation of the plate 85. The disk 87 is cut away at one side to provide a suitable recess 87^a to accommodate the extended portions 90 of the plate 85. The operation of this mechanism is well known and need not be described in detail, it being sufficient to state that as the disk 87 is rotated the pin 89 engaging the slot 86 in the plate 85 will 10 rotate the plate and the turret therewith about the axis of the driving shaft one sixth of a revolution at which time the pin 89 will leave the slot and the disk 87 will be positively locked from further rotation by the engagement of the periphery of the disk 87 with an arcuate portion of the edge of the disk 85. While this locking mechanism might ordinarily be sufficient to prevent relative lateral movement of the work supporting chucks of the tool holders, an indexing mechanism is provided which will 20 positively prevent any rotary movement or vibration of the turret when the spindles and tools are in coöperating position.

In the preferred embodiment of the invention illustrated in the accompanying drawing the head 18 of the turret is provided with a series of recesses 91 (see Fig. 2) which are adapted to be engaged by the end of the pin 92 which is slidably mounted in a bracket 93 secured to the frame of the machine. The pin 92 desirably is normally thrust forward by a spring 93^a and may be provided with a slot 94 adapted to receive the spherical or cylindrical end of the lever 95 pivotally mounted upon the frame and at its opposite end having an anti-friction roller 96 engaging a cam 97 upon the cam shaft 70. The cam 97 is so constructed as to 30 cause the withdrawal of the pin 92 from locking engagement with the socket 91 at the time the pin 89 on the disk 87 engages the wall of the slot 86 to rotate the turret. The cam 96 is so cut away as to release the end of the lever 95 and permit the spring to throw the pin 92 into engagement with a socket 91 immediately after the pin 89 leaves the slot 86 in the plate 85.

In view of the fact that the indexing pin 92 engages directly the head of the turret which supports the chuck receiving ends of the spindles 22 a maximum efficiency in locking against rotary movement is obtained.

By actuating the cam drum, the "Geneva" stop mechanism, and the indexing mechanism from the same cam shaft an exact coordination of the timing of the various parts is insured. If desired one or more cross feeding tools may be provided by arranging suitable brackets for the support thereof and

actuating the same from the cam shaft 70. One of said tools which is illustrated herein comprises a cross-cut tool 100 which is slidably supported upon a bracket 101 carried by the web 71 said tool being forced toward the work by a bell crank lever 102 which is pivotally mounted upon a stud shaft 103 carried by brackets 104 forming a part of or secured to the frame 2, the opposite arm 105 of the bell crank lever engaging a cam 106 fixedly secured upon the cam shaft 70.

Other cross feeding tools may be mounted in the same or any other suitable manner and actuated either directly or indirectly from the cam shaft 70 so that the proper timing relation of said tools in respect to the rotating turret may be preserved.

By providing the clutch mechanism for the countershaft 75 which connects the main shaft to the cam shaft means are provided whereby the rotation of the cam drum and consequently the actuation of the tool holders may be stopped instantly at the will of the operator. This is quite essential if the work has not been properly chucked or is found too hard to be machined, and such stoppage of the drum will not throw the same out of timing for the reason that the drum is rotated from the cam shaft 70 which also actuates the "Geneva" stop mechanism. Under such conditions the rotation of the work holding spindles continues and may continue on until the machine is stopped by the usual throwing off of the power.

In the normal operation of the machine the work holding spindles are driven through the gears 34 which may be driven at a relatively high speed. To accomplish this purpose means are provided for retaining the clutches 39 in engagement with the gear 34 throughout the major part of the rotation of the turret. This is conveniently accomplished by providing a bracket 110 adapted to support a cam plate 111 which is substantially circular in form and is provided with a face 112 adapted to force the ends of the rods 42 forward, or to the right as illustrated in Fig. 1, a sufficient distance to maintain the clutch 39 in constant engagement with the clutch face of the gear 34. In order to permit the reversal of the work holding spindles during the timing operations aforesaid one or more portions of the cam plate 111 may be provided with suitable recesses 113, 114 to permit the movement of the rod 42 in the opposite direction and the shifting of the clutch by the rod 66 which is secured to the holders 55^a in the manner above described.

In the operation of the machine the work is inserted by the operator in the chuck which is in opened position by reason of the fluid actuating mechanism for said chuck being connected with the exhaust port. Ample time is given to the workman for this

purpose for the reason that the chuck remains open during one of the operations of the tools upon the work or in other words nearly one sixth of the time required for the 5 rotation of the turret. When the operations of the tool are completed the turret is rotated a step forward by the "Geneva" stop mechanism and as the chuck advances to its operative relation to the first tool in the 10 series the port of the tube 48 is placed in communication with the fluid supply which immediately fills the chamber behind the piston 25 and causes the clutch to grip tightly the article to be operated upon. 15 When the work supporting spindle has reached a position to coöperate with the first tool, the rotation of the turret is stopped and the turret locked from further movement by the operation of the indexing 20 mechanism. The tools are then all advanced by the cam drum 56 or by the cam upon the cam shaft 70 as the case may be to perform an operation upon the work. In the meantime another piece of work is chucked into 25 the next succeeding spindle. The operation is then repeated so that the work is operated upon successively by each of the tools in the series, all of the tools being forced forward simultaneously into engagement with the 30 work by the action of the cams upon the cam drum or cam shaft. If a piece of work has not been properly chucked or if the same is found to be imperfect or too hard to be operated upon by one of the tools the advance 35 of the tool may be stopped by throwing out the clutch members 78, 79 through the operation of the lever 80 as is usual in machines of this character.

While the construction herein disclosed 40 illustrates a preferred embodiment of my invention it will be understood that the same may be embodied in other forms or that equivalent mechanisms may be substituted for certain of the mechanisms herein 45 within the spirit and scope of the following claims it being particularly remembered that the construction is illustrative and not restrictive as to the features of the invention which are broadly novel.

50 Having thus described my invention what I claim as new and desire to secure by Letters Patent is:

1. A machine of the class described comprising a turret having a closed casing forming a chamber for a body of lubricant, means for intermittently rotating the same, a plurality of spindles journaled in said turret and means within said turret for actuating said spindles whereby the spindle actuating 55 means will run in lubricant during a portion of each revolution of the turret.

2. A machine of the class described comprising a turret having a closed casing forming a chamber for a body of lubricant, 60 means for intermittently rotating the same,

a plurality of spindles journaled in said turret, independent means within said turret for rotating said spindles in either direction, and clutch mechanism within said turret for controlling the direction of rotation of said 70 spindle, said spindles and clutch mechanism being adapted to run in lubricant during a portion of each revolution of the turret.

3. In a multi-spindle machine comprising 75 a turret having a closed casing forming a chamber for a body of lubricant, and means for intermittently rotating the same and a plurality of spindles journaled in said turret, gearing within said turret for rotating 80 said spindles in either direction, means for controlling the direction of rotation of said spindles, and means extending through the end of said turret for actuating said controlling means, whereby the spindle rotating 85 means and said controlling means may be immersed in lubricant during a portion of each revolution without loss of lubricant from the casing.

4. In a multi-spindle machine comprising 90 a frame having stands provided with alined bosses forming journals, a driving shaft mounted in said bosses, a turret mounted upon said bosses and rotatable about the axis of said driving shaft, a plurality of work 95 carrying spindles journaled in said turret, independent means within said turret operable from said driving shaft for rotating said spindles in either direction and means for controlling the direction of rotation of 100 each spindle.

5. In a multi-spindle machine comprising a frame having stands provided with alined bosses, a driving shaft mounted in said bosses, a turret having a hub mounted on 105 said bosses and rotatable about the axis of said driving shaft, means for intermittently rotating said turret, a plurality of work carrying spindles journaled in said turret, means for rotating said spindles, tool spindles arranged in coöperative relation to said work carrying spindles and means for reciprocating said tool spindles.

6. In a multi-spindle machine comprising 110 a frame having stands provided with alined bosses, a driving shaft mounted in said bosses, a turret having a hub mounted on said bosses and rotatable about the axle of said driving shaft, and means for intermittently rotating the same, a plurality of work 115 carrying spindles journaled in said turret, two gears rotatably mounted upon each of said spindles within said turret, means operated by the driving shaft for rotating said gears in opposite directions and a clutch 120 slidably secured to said spindles intermediate of said gears and adapted alternatively to engage either of said gears, tool spindles arranged in operative relation to said work carrying spindles, means for re- 125 130

ciprocating said tool spindles and means operable by the reciprocation of certain of said tool spindles to cause the shifting of the clutch whereby the direction of rotation of the work carrying spindles will be reversed.

5 7. In a multi-spindle machine comprising a frame, a driving shaft mounted therein, a turret rotatable about the axis of said driving shaft, a plurality of work carrying spindles journaled in said turret, two gears mounted rotatably upon each of said spindles within said turret, a clutch secured to said spindles intermediate of said gears and adapted alternatively to engage either of

10 said gears, means operated by said shaft for rotating said gears in opposite directions whereby the clutch is adapted to cause rotation of the work holding spindle in either direction and resilient means tending normally to restore the clutch to an intermediate neutral position out of engagement with both of said gears.

15 8. In a multi-spindle machine, a rotatable turret, a series of work carrying spindles journaled in said turret, a series of tool holders and means for actuating the same, means for intermittently rotating said turret to position said spindles successively in operative relation to each of said tool holders, means for rotating said spindles in either direction, clutches carried by said spindles adapted alternatively to engage said spindle actuating means, resilient means normally tending to maintain said 20 clutches in neutral positions, means for forcing said clutches during a portion of the revolution of the turret into engagement with said spindle rotating means to cause rotation of the spindles in one direction, means carried by certain of said tool holders adapted upon the release of said clutch actuating means to force the clutch into engagement with the oppositely rotating spindle actuating means, the action of said resilient means serving to speed up the shifting of the clutch and the consequent reversal of the spindles.

25 9. In a machine of the class described comprising a spindle, means for rotating the same including a clutch adapted operatively to connect said spindle and said spindle rotating means, resilient means adapted normally to force the clutch into inoperative position and clutch actuating means for forcing said clutch into operative position against the force of said resilient means whereby upon the release of the clutch actuating means rapid disengagement of the clutch will be effected.

30 10. In a multi-spindle machine comprising a rotatable turret, a plurality of work carrying spindles journaled in said turret and means for actuating the same, a support having a series of tools mounted to co-

35 operate successively with said work spindles, a cam drum rotatably mounted in said tool support, means rigidly connected to said tool supports adapted to engage respectively the cams on said drum and the walls of slots in said support and thereby to cause longitudinal movement of the tool spindles to prevent rotation of the tool.

40 11. In a multi-spindle machine comprising a rotatable turret, a plurality of work carrying spindles journaled in said turret and means for actuating the same, a support having a series of tools mounted to co-operate successively with said work spindles, means adjustably secured to said tool supports having extensions adapted to engage respectively the cams on said drum and the walls of slots in said support.

45 12. In a multi-spindle machine comprising a frame, a driving shaft, a turret rotatably mounted upon said driving shaft, a plurality of work carrying spindles journaled in said turret, means operable from said driving shaft for rotating said spindles, a head having a plurality of non-rotatable tool holders, means for rotating said turret to position the work carrying spindles successively in co-operative relation to each of said tool holders, a cam drum mounted for rotation about the axis of said main shaft, means on said tool holders engaging the cams on said drum whereby said tool holders will be reciprocated in an axial direction of the work holding spindles and means for rotating said cam drum in timed relation to the rotation of said turret.

50 13. In a multi-spindle machine comprising a rotatable turret, means for intermittently rotating the same a predetermined amount, indexing means for locking said turret, a plurality of work carrying spindles journaled in said turret and means within said turret for rotating said spindles in either direction including clutch mechanism adapted to control the direction of rotation of each spindle, a plurality of axially movable tool holders co-operatively arranged in respect to said work carrying spindles, means for reciprocating said tool holders in the axial direction of said spindles and means carried by certain of said tool holders adapted to engage said clutch mechanism to reverse the rotation of the work carrying spindle which cooperates with said holder.

55 14. In a multi-spindle machine comprising a frame, a driving shaft mounted therein, a turret mounted to rotate about the axis of said driving shaft, a plurality of spindles journaled in said turret, means operable by said driving shaft for rotating said spindles in either direction including clutch mechanism for controlling the direction of rotation of said spindles, a cam shaft, means for actuating the same from said driving shaft, means operated from the cam shaft for rotating said turret, a cam drum mount-

ed for rotation about the axis of said main shaft, means for actuating said drum from said cam shaft, and a plurality of tool slides independently operable by said drum in the 5 axial direction of said tool spindles.

15. In a multi-spindle machine comprising a frame, a driving shaft mounted therein, a turret rotatably mounted about the axis of said driving shaft, a series of work supporting spindles journaled in said turret, means for alternatively rotating said work carrying spindles in either direction, a support having a series of tool holders slidably mounted therein and arranged in cooperative relation to said spindles, a drum mounted for rotation about the axis of said driving shaft having cams for actuating said tool holders, means for rotating said cam shaft from said main shaft and means actuated by said cam shaft respectively to rotate the turret intermittently, to index said turret and to rotate said tool actuating drum whereby the proper timing of the parts is preserved at all times.

25. 16. In a multi-spindle machine comprising a frame, a driving shaft mounted therein, a turret rotatably mounted about the axis of said driving shaft, a series of work supporting spindles journaled in said turret, means 30 for alternatively rotating said work carrying spindles in either direction, a support having a series of tool holders slidably mounted therein and arranged in cooperative relation to said spindles, a drum mounted for rotation about the axis of said driving shaft having cams for actuating said tool holders, means for rotating said cam shaft from said main shaft and means actuated by said cam shaft respectively to rotate the 35 turret intermittently, to index said turret and to rotate said tool actuating drum whereby the proper timing of the parts is preserved at all times and means for rendering inoperative the means for transmitting rotation 40 from the driving shaft to the cam shaft.

17. In a multi-spindle machine comprising a rotary turret, a plurality of rotatable spindles journaled in said turret, fluid operated chucks in said spindles including

means for automatically introducing fluid 50 under pressure to close said chucks at a predetermined position during the revolution of said turret and means for releasing said fluid at a different predetermined position.

18. In a multi-spindle machine comprising 55 a main frame having an extended journal forming a bearing for a driving shaft, a turret having a head rotatably mounted upon said journal, a plurality of spindles rotatably mounted in said turret, work carrying chucks mounted in said spindle, fluid operated means for closing said chucks including a piston connected to said chuck jaws and a cylinder inclosing the piston, ducts leading from said cylinders to ports in said 60 hub, a fluid chamber adapted to communicate with the ports in said hub, means for supplying fluid under pressure to said chamber during a predetermined portion of the revolution of said hub to cause the chuck 65 to grip the work, and an exhaust chamber in said journal in the path of the ports in said hub positioned automatically to release the fluid under pressure from the cylinder at a different predetermined portion of the rotation 70 of said turret to permit removal of the work.

19. In a multi-spindle machine comprising 75 a rotary turret, a plurality of spindles journaled in said turret, said spindles comprising a sleeve and means for rotating the same, a chuck mounted in said sleeve, a rod connected to said chuck at one end and at its opposite end to a piston, a cylinder inclosing 80 said piston secured to the opposite end of said sleeve, automatically operable means for introducing fluid under pressure to said cylinder while the spindle is rotating and during a predetermined portion of the revolution 85 of said turret to close the chuck upon the work and means for automatically exhausting said cylinder during a different predetermined portion of the revolution of said turret whereby the work will be released.

In testimony whereof, I have signed my name to this specification.

FREDERICK K. NORTH.
